ATTORNEY

UNITED STATES PATENT OFFICE

JOSEPH A. LOWE, OF FITCHBURG, MASSACHUSETTS, ASSIGNOR TO FALULAH PAPER COMPANY, OF FITCHBURG, MASSACHUSETTS, A CORPORATION OF MASSACHUSETTS

PAPER

Application filed December 11, 1928. Serial No. 325,260.

This invention relates to paper and more specifically to paper having an improved identification means normally hid from view but observable when the paper is torn.

5 A primary object of the invention is therefore to provide a sheet of paper or a card composed of any desired number of plies, at least one inner ply being of unfinished composition as distinguished from the outer plies and 10 which more freely absorbs moisture than do the outer plies, so that this inner ply is impregnated with a color ingredient which gives a streaky or mottled effect to such inner ply, and when the sheet or card is torn this streaky 15 or mottled coloring effect is readily observable to indicate the product of the manufacturer.

With these and other objects in view, the invention consists in certain novel features of 20 construction and combinations and arrangements of parts, which will be more fully hereinafter described and pointed out in the claims.

In the accompanying drawings—

25 Figure 1 is a fragmentary plan view showing the inner ply of the sheet or card with a colored paste thereon;

Figure 2 is an exaggerated plan view of Figure 1;

30 Figure 3 is an exaggerated edge view of the completed sheet or card with the outer plies in place;

Figure 4 is a fragmentary plan view showing the several plies of the sheet or card 35 broken away;

Figure 5 is a fragmentary plan view showing my completed sheet or card with a corner torn off to expose the streaky coloring of the inner ply.

40 It is of course to be understood that the illustrations are more or less diagrammatic, as the machine or apparatus employed for making the paper may be constructed in various ways, and the drawings are not intended to be illustrative of a method but

merely to illustrate more specifically the invention as it exists in the article itself.

1 represents an inner ply and 2 or 3 outer plies which are secured to opposite faces of the inner ply 1. These plies 1, 2 and 3 50 are secured together by paste or other suitable adhesive which contains a color, and I have used the reference character 4 in Figures 1 and 2 to indicate the paste as a thickness but which, as a matter of fact, ceases 55 to be a thickness and impregnates the plies and more particularly the inner ply when the sheet or card is formed.

By employing a paste or other adhesive containing a color I have discovered that 60 by reason of the absorption of moisture of the glue by the inner ply 1, which is more porous than the outer plies 2 and 3, the coloring matter in the paste will impregnate the inner ply 1 but will not give a uniform 65 color. In other words, this color will be mottled or streaked throughout the inner ply and the color will not affect or come through the outer plies 2 and 3.

When a corner of the sheet or card is torn, 70 as indicated in Figure 5, the inner ply 1 will show the color in streaks or mottled formation and this will prove the goods of the manufacturer.

I of course do not wish to limit myself to 75 any particular color nor to any particular medium for making the color but I desire to cover broadly the idea of a sheet of paper or a card in which at least one inner ply is impregnated with a color so that said 80 color is not a solid color throughout the ply but has a mottled or streaky appearance.

I claim:

1. A multi-ply paper comprising outer plies, an inner ply, and a colored adhesive 85 with which the inner ply is impregnated, the adhesive connecting the outer plies and the color providing a hidden identification stratum.

2. A multi-ply paper comprising outer 90

plies, a colored adhesive, and an inner ply more porous than the outer plies being impregnated with said adhesive for the connection of the outer plies, but causing an uneven distribution of the color, said inner ply remaining hidden until the paper is torn on a bias cross-sectionally.

3. Paper comprising a pair of plies, and a colored adhesive to secure the plies in homogeneous sheet form.

JOSEPH A. LOWE.
